UNITED STATES PATENT OFFICE.

SYLVESTER A. LANGENBAKER, OF SAN FRANCISCO, CALIFORNIA, ASSIGNOR TO MAG-BETH-EVANS GLASS COMPANY, OF CHARLEROI, PENNSYLVANIA, A CORPORATION OF PENNSYLVANIA.

DESIGN FOR A GLASS JUG.

Application filed April 19, 1928. Serial No. 26,378. Term of patent 3½ years.

To all whom it may concern:

Be it known that I, SYLVESTER A. LANGENBAKER, a citizen of the United States, residing at San Francisco, in the county of San Francisco and State of California, have invented a new, original, and ornamental Design for Glass Jug, of which the following is a specification, reference being had to the

accompanying drawing, forming a part thereof.

The figure is a perspective side view of a glass jug, showing my new design.

I claim:

The ornamental design for a glass jug, as shown.

SYLVESTER A. LANGENBAKER.
